DESIGN FOR A WOMAN'S SUIT

Morris Goldman, San Francisco, Calif.

Application February 9, 1935, Serial No. 55,323

Term of patent 3½ years

To all whom it may concern:

Be it known that I, Morris Goldman, a citizen of the United States and a resident of the city and county of San Francisco, State of California, have invented a new, original, and ornamental Design for a Woman's Suit, of which the following is a specification, reference being had to the accompanying drawing, forming part thereof.

Referring to the drawing:

Fig. 1 is a front view of a woman's suit showing my new design.

Fig. 2 is a rear view of the woman's suit shown in Fig. 1.

The woman's suit of my invention is especially characterized by a coat having a yoke at the back bounded by an arched lower edge below which is a full, gathered area, and bounded by a pair of inverted arched seams at the back of the shoulders, from each of which a panel extends upwardly and forwardly over the shoulder. The gathered area terminates in a partial belt, leaving the sides and the remainder of the coat smooth and closely fitted. The front of the coat is characterized by military pockets, each with a central, inverted pleat.

I claim:

The ornamental design for a woman's suit, as shown and described.

MORRIS GOLDMAN.
